UNITED STATES PATENT OFFICE.

ARTHUR E. RIEDEL, OF NEW YORK, N. Y.

SNOW-MELTING APPARATUS.

SPECIFICATION forming part of Letters Patent No. 734,195, dated July 21, 1903.

Application filed January 27, 1903. Serial No. 140,698. (No model.)

To all whom it may concern:

Be it known that I, ARTHUR E. RIEDEL, a citizen of the United States, residing at New York, in the county of New York and State of New York, have invented certain new and useful Improvements in Snow-Melting Apparatus, of which the following is a specification, such as will enable those skilled in the art to which it appertains to make and use the same.

The object of this invention is to provide an improved apparatus for melting snow, whereby accumulated snow in the streets of cities and towns may be more conveniently disposed of and at a less expense than is possible by present methods.

The invention is fully disclosed in the following specification, of which the accompanying drawings form a part, in which the separate parts of my improvement are designated by suitable reference characters in each of the views, and in which—

Figure 1 is a side elevation of a snow-melting apparatus involving my invention; Fig. 2, a sectional side elevation thereof; Fig. 3, a cross-section on the line 3 3 of Fig. 1, and Fig. 4 a similar section on the line 4 4 of Fig. 1.

In the practice of my invention, as shown in the drawings, I provide a truck-frame *a*, which may be of any suitable or desirable construction and which is provided at each end with axles and wheels *b*. The truck-frame *a* is preferably rectangular and oblong in form and composed of side members *a*², connected by end members *a*³, and mounted over this frame is a supplemental frame *c* of the same general form and provided at its rear end with a shaft *c*², having bearings *c*³ on the main truck-frame. The main truck-frame is also provided near its front end with a transverse member *a*⁴, through which are passed vertically-arranged jack-screws *d*, and the supplemental frame *c* is provided with a cross member *c*¹, on which said jack-screws bear, and by means of this construction the front end of the supplemental frame *c* may be raised or lowered whenever desired. Arranged rearwardly of the front portion of the supplemental frame and at each side thereof are flanged rollers *e*, said rollers being arranged in transverse pairs, and mounted on

these rollers is a cylindrical casing *f*, having annular tracks or ways *g*, which bear on the rollers *e*. The cylindrical casing *f* is also provided with an annular gear *g*², and supported longitudinally of the supplemental frame and beneath the same is a shaft *h*, having a gear-wheel *h*², which operates in connection with the annular gear *g*², and the front end of this device is provided with a crank-wheel *h*³, and supported over said crank-wheel and over the front end of the supplemental frame is a gasoline or other suitable motor *h*⁴, the piston of which is in operative connection with the crank-wheel *h*³ by means of a rod *h*⁵.

Within the cylindrical casing *f* and arranged concentrically with relation thereto is a supplemental cylindrical casing *i*, which is provided with longitudinal rows of perforations *i*², and within this supplemental cylindrical casing *i* and secured to the inner walls thereof are longitudinally-arranged stirrers *j*, perforated longitudinally, as shown at *j*², and the inner edges of which are preferably curved or bent at an angle to the body portion thereof, the curves or bends being preferably all in the same direction and being in the direction of the revolution of the casings *f* and *i*, and between the casings *f* and *i* is an annular space *k*.

At the front end of the casing *f* is placed a fire-box *m*, similar to the fire-box of a boiler, and over this fire-box is placed a hopper *m*², having a discharge-spout *m*³, which is directed downwardly and backwardly and adapted to discharge snow into the open front end of the supplemental inner casing *i*. It will be observed that both of the casings *i* and *f* are open at the front ends and also at their rear ends, and the casing *i* is preferably provided at its rear end with an inwardly-directed flange or rim *i*³, whereby a reduced opening *i*⁴ is formed, and, if desirable, an escape or draft flue may be placed so as to communicate with the open rear end of the casing *i*.

The fire-box *m* is provided in the form of construction shown and in one side with a door *m*⁴ and with the usual grate *m*⁵, and in practice a fire is started in the fire-box and the flame, the hot gases, and other escaping products of combustion pass backwardly through the casing *i* in the manner of an or-

inary boiler, and said casing *i* is highly heated, together with the stirrers or agitators *j*. The snow is thrown into the hopper *m*² and passes downwardly through the chute *m*³, which is also highly heated, and is discharged into the casing *i*, which is constantly revolved by means of the engine or motor *h*⁴, and in this operation the snow is constantly lifted by the stirrers or agitators *j* and constantly dropped from a higher to a lower position and gradually moves backwardly to the rear end of the casing *i*, over the bottom of said casing, and along the stirrers or agitators *j*, and in this operation all the snow is quickly melted and the melted water flows through the holes *i*² in the casing *i* and into the outer casing *f*, which is also constantly revolved, and out at the rear end of said casing.

It will be apparent that the casing *f* and fire-box *m* may be rearranged, or, in other words, the fire-box may be put at the rear end of the casing *f*, in which event the rear end of said casing would be adapted to be raised and lowered, and any suitable fuel may be employed in the fire-box, and oil-ejector burners may be used, and various other changes in and modifications of the construction herein described may be made without departing from the spirit of my invention or sacrificing its advantages. It will also be apparent that my improved snow-melting apparatus may be conveniently moved from one point to another in the manner of an ordinary truck or portable engine, and my invention is not limited to the means herein described for rotating the casing *f* and the casing *i* therein, and any suitable mechanism for this purpose may be employed.

Having fully described my invention, what I claim as new, and desire to secure by Letters Patent, is—

1. In a snow-melting machine, a frame vertically movable at one end, a revoluble cylindrical casing mounted thereon, a supplemental casing supported concentrically within the first-named casing and open at both ends, and a fire-box mounted on said frame at one end of said casings and adapted to discharge heat into the supplemental casing, said fire-box being provided with a hopper adapted to discharge into the supplemental casing, substantially as shown and described.
2. In a snow-melting machine, a truck-frame, a supplemental frame mounted thereon and vertically movable at one end, a hollow revoluble casing mounted on said supplemental frame, a supplemental casing ar-

ranged in said first-named casing and open at both ends, and a fire-box arranged at one end of said casings and adapted to discharge heat into the supplemental casing and provided with a hopper also adapted to discharge into the supplemental casing, substantially as shown and described.

3. In a snow-melting machine, a frame vertically movable at one end, a rotatable casing mounted on said frame and open at both ends, a supplemental casing placed concentrically in the first-named casing and open at both ends, a fire-box mounted at one end of the supplemental casing and adapted to discharge heat thereinto and provided with a hopper also adapted to discharge into the supplemental casing, said supplemental casing being perforated and provided with longitudinally-arranged agitators, substantially as shown and described.

4. In a snow-melting machine, a frame, a revoluble casing mounted on said frame, a supplemental casing arranged concentrically in the first-named casing and perforated and open at both ends and provided with longitudinally-arranged agitators or stirrers, and a fire-box supported on said frame at one end of said casings and adapted to discharge heat into the supplemental casing and provided with a hopper also adapted to discharge into the supplemental casing, substantially as shown and described.

5. In a snow-melting machine, a truck, a supplemental frame mounted thereon, means for raising and lowering one end of said supplemental frame, a longitudinally-arranged and revoluble casing mounted on said supplemental frame, a supplemental casing mounted concentrically in the first-named casing and perforated and open at both ends and provided with longitudinally-arranged stirrers or agitators, and a fire-box supported on the supplemental frame at one end of said casings and adapted to discharge heat into the supplemental casing and provided with a hopper also adapted to discharge into the supplemental casing, substantially as shown and described.

In testimony that I claim the foregoing as my invention I have signed my name, in presence of the subscribing witnesses, this 24th day of January, 1903.

ARTHUR E. RIEDEL.
